UNITED STATES PATENT OFFICE.

GEORGE W. WARREN AND FRED D. CLARK, OF PRATTSBURG, NEW YORK.

TRELLIS.

SPECIFICATION forming part of Reissued Letters Patent No. 11,622, dated July 20, 1897.

Original No. 581,896, dated May 4, 1897. Application for reissue filed June 12, 1897. Serial No. 640,560.

To all whom it may concern:

Be it known that we, GEORGE W. WARREN and FRED D. CLARK, citizens of the United States, residing at Prattsburg, in the county 5 of Steuben and State of New York, have invented a new and useful Trellis, of which the following is a specification.

This invention relates to improvements in trellises for flower-pots and similar receptacles; and the object of the invention is to provide a trellis of the character mentioned which is adapted to support and train plants of any size grown in flower-pots and similar receptacles and so to construct the trellis as 15 to permit the same to be readily attached to or detached from receptacles of various designs, shapes, and sizes.

The invention further aims to provide a trellis the use of which will not disfigure the 20 plants or interfere with the roots thereof and will enable the receptacle to be easily lifted and moved, the trellis serving in the capacity of a handle and firmly holding such receptacle.

With these objects in view the invention 25 consists, substantially, in the construction, combination, and arrangements of parts, as will be hereinafter fully illustrated, described, and claimed.

In the accompanying drawings, Figure 1 is 30 a perspective view of a trellis constructed in accordance with the present invention and illustrated in applied position. Fig. 2 is a detail perspective view of the lower portion 35 of one side of the trellis and illustrating the means for holding the trellis upon a flower-pot or similar receptacle. Figs. 3 and 4 are perspective views, on a reduced scale, of modifications of the trellis. Fig. 5 is a detail sectional view of the lower portion of one side 40 of the trellis, showing the clutch in position upon a flower-pot.

Similar numerals of reference indicate corresponding parts throughout the figures.

Referring to the drawings, 1 designates a 45 body-frame which is preferably formed of steel wire and is bent into a substantially inverted-U shape or any other desired form.

Within the body-frame 1 is a centrally-arranged brace-frame 2, which brace-frame is 50 formed of the same material as said body-frame and conforms to the general contour

thereof. The brace-frame 2, as it will be noted, is bent from a single piece, and the sides of the brace-frame are twisted, as at 3, so as 55 to form a substantially elliptical-shaped loop 4, which lies at approximate center of the body-frame 1. The sides of the brace-frame 2, below the twisted portion 3, diverge and extend substantially parallel with the sides 60 of the body-frame 1 to a point adjacent to the lower portions of said sides of the body-frame, where they are sharply bent outwardly, as at 5, and are twisted with the lower terminals of the sides of said body-frame for any de- 65 sired distance, as indicated at 6.

The lower end of each of the twisted portions 6 is bent outwardly and then provided with a sharp inward curve to form a contact-point 7, which is adapted to bear against the 70 under side of the rim of a flower-pot or similar receptacle for a purpose to be presently explained. Extending in opposite directions from the contact-points 7, the lower terminals of the sides of the body-frame and the 75 brace-frame 2 are separated and bent to form attaching-hooks 8, which consist of upper curved portions to extend over the upper edge of a flower-pot and depending portions to engage the inner face thereof, the contact-point and the hooks at each side of the trellis 80 constituting a spring-catch. It will therefore be seen that by reason of said terminals being bent into the hooks 8 said hooks may be placed over the sides of a flower-pot or similar receptacle and project on the interior 85 thereof, the contact-points 7 extending beneath the rim of said pot and together with the attaching-hooks clutching the pot to securely hold the trellis upon the same. 9c

A filling 9 is secured to the body-frame 1 and extends thereover to provide a surface upon which a plant may be supported and trained, and said filling may be of any preferred construction and of any suitable material adapted for the purpose to which it is applied. 95

In Fig. 3 a modification of the trellis is illustrated, and in this form it will be noted that the brace-frame is arched, as at 10, the loop 100 4 being dispensed with, but the lower terminals at the sides of the brace-frame being twisted with the lower terminals of the sides of the body-frame 1, as in Fig. 1. It is also

to be observed that the means for attaching the trellis to a flower-pot or similar receptacle is slightly changed, the twisted portion of the sides being straight, but the lower terminals 5 of the sides of the body-frame and the brace-frame being separated and bent to form attaching-hooks 11, said hooks extending in opposite directions to the hooks 8. (Shown in Fig. 1.) This modified construction provides 10 a trellis which, though not as strong as the form shown in Fig. 1, is sufficient for use with small plants.

Fig. 4 also represents a further modification, and in this form it will be seen that the 15 brace-frame 12 is again differently arranged, said frame having its sides spirally wound around the body-frame 1 and the lower terminals of said sides twisted with the lower terminals of the sides of the body-frame in a 20 manner similar to that shown in Figs. 1 and 3. The twisted portion of the sides and the attaching-hooks in this form are the same as shown in Fig. 1, and by arranging the brace-frame as described the trellis is adapted for 25 use with tall plants, it being obvious that the latter may readily pass up through the center of the trellis and be supported by the convolutions of the brace-frame.

While we have shown modifications of the 30 trellis in Figs. 3 and 4, the form illustrated in Fig. 1 is preferred from the fact that the same is stronger and thereby better adapted for a variety of uses, and by constructing the attaching-hooks so as to provide clutches the 35 trellis will be securely held upon a flower-pot or similar receptacle without liability of displacement.

The manner of using the herein-described trellis will be apparent to those skilled in the 40 art. When it is desired to apply the same to a flower-pot or similar receptacle, the attaching-hooks 8 are placed over the sides thereof at opposite points and the contact-points forced beneath the rim, as described. This 45 will securely hold the trellis upon the pot, and by reason of the brace-frame 2 being connected to the sides of the body-frame 1 and extending in the position illustrated and described it will be seen that said brace-frame 50 strengthens said body-frame and at the same time firmly braces the filling 9, which covers the trellis, so that as the plant rests against said filling the latter will be prevented from bending and retain its original shape and also 55 the grace of the trellis.

From the foregoing it will be seen that we have provided a trellis which is simple, inexpensive, durable, and efficient and also one which is adapted to support and train plants 60 of any size grown in flower-pots and similar receptacles and so constructed as to permit the same being readily attached to or detached from receptacles of various designs, shapes, and sizes. By the use of the trellis 65 the plants will not be disfigured, nor will the roots thereof be interfered with, but said trellis may serve in the capacity of a handle,

and thus permit the flower-pots or similar receptacles to be easily lifted and moved—a feature which is very desirable in crowded flower-stands and conservatories when the plants are to be watered or moved for other purposes. Furthermore, the trellis may be attached to receptacles having either straight or sloping sides and constructed of thick or thin material, and in the event that it is desired to suspend the receptacles in which the plants are growing it will also be seen that the same may be accomplished from the fact that the trellis is securely held thereon and will there- 75 80 85 by firmly hold the receptacle in such suspended position.

Having thus described the invention, what is claimed as new, and desired to be secured by Letters Patent, is—

1. A trellis having at one end a clutch composed of curved elastic members to engage the inside of a flower pot or receptacle, and a projecting contact-point to extend under and engage the bead, rib or flange on the pot, 90 or receptacle, whereby the trellis serves as a handle to carry the latter, substantially as described.

2. A trellis, consisting of a bail-shaped frame having a pair of clutches constructed with projecting contact-points to engage under the bead, rib or flange on a flower-pot, or other receptacle, whereby the trellis is interlocked with the receptacle and constitutes a handle for carrying the latter, substantially 100 as described.

3. A trellis, consisting of a wire frame having its lower end portion twisted and formed into a clutch comprising a sharp inward curve to provide a contact-point and arms or terminals extending in opposite directions from said contact-point and bent into elastic clutch-hooks, the contact-point constructed to engage under the bead or rib on a flower-pot and the elastic clutch-hooks constructed to 105 bear against the inside of the pot, substantially as described.

4. A trellis, consisting of a wire frame having its lower end portion twisted and formed into two opposite clutches, each comprising 110 an inward curve to provide a contact-point and two arms or terminals extending from said contact-point and bent into clutch-hooks, substantially as and for the purposes 115 described.

5. A trellis, consisting of a frame having hooked terminals bent outwardly and provided with sharp inward curves to form contact-points for engaging the outer face of a flower-pot under the rib or shoulder at the 120 top thereof, the hooks being arranged in pairs at the contact-point of each side of the trellis, and composed of upper curved portions to extend over the upper edge of the flower-pot and depending portions forming contact-points for 125 engaging the interior of the pot, said hooked terminals forming spring-catches, substantially as described.

6. A trellis, comprising a body-frame, a

- brace-frame connected thereto and adapted to strengthen the same, and means for attaching the trellis to a flower-pot or similar receptacle, substantially as set forth.
- 5 7. A trellis, comprising a body-frame, and a brace-frame connected to said body-frame and adapted to strengthen the same, the ends of said brace-frame being connected to the ends of the body-frame and forming clutches 10 adapted to hold the trellis upon a flower-pot or similar receptacle, substantially as set forth.
8. A trellis, comprising a body-frame, and a brace-frame, connected to said body-frame, the ends of said brace-frame and the body-frame being twisted and forming clutches 15 adapted to secure the trellis detachably to a flower-pot or similar receptacle, substantially as set forth.
9. A trellis, comprising a body-frame, and 20 a brace-frame connected to said body-frame, formed of a single piece and having its sides twisted to provide a loop arranged at approximately the center of the body-frame, said sides being extended from said loop and together 25 with the sides of the body-frame twisted and forming clutches adapted to secure the trellis to a flower-pot or similar receptacle, substantially as set forth.
10. A trellis, comprising a body-frame, and 30 a brace-frame connected to said body-frame and adapted to strengthen the same, said brace-frame being formed of a single piece and having its sides twisted to form a loop, said sides diverging from said loop and having 35 their lower terminals twisted with the lower terminals of the sides of the body-frame, the terminals of each side of the body-frame and the brace-frame at each side of the trellis extending in opposite directions and forming 40 attaching-hooks adapted to secure the trellis to a flower-pot or similar receptacle, and a filling secured to the body-frame and extending thereover, substantially as set forth.
11. A trellis, comprising a body-frame, and 45 a brace-frame connected to said body-frame and adapted to strengthen the same, said brace-frame being formed of a single piece and having its sides twisted to provide a loop arranged at approximately the center of the 50 body-frame, said sides diverging from said loop and each having its lower terminal twisted with the lower terminal of one side of the
- body-frame, said twisted terminals of the body-frame and the brace-frame being bent outwardly and provided with a sharp inward 55 curve to form a contact-point, the terminals of each side of the body-frame and the brace-frame at each side of the trellis extending in opposite directions from said contact-point and being bent to form attaching-hooks, the 60 contact-point and attaching-hooks at each side of the trellis constituting a clutch, said clutches being adapted to secure the trellis to a flower-pot or similar receptacle, substantially as set forth.
12. A trellis, comprising a body-frame and a brace-frame having hooked terminals bent outwardly and provided with a sharp inward curve to form contact-points for engaging the outer face of a flower-pot under the rib or 70 shoulder at the top thereof, the hooks being arranged in pairs at the contact-point of each side of the trellis, and consisting of upper curved portions to extend over the upper edge of a flower-pot and depending portions 75 forming contact-points for engaging the interior of a flower-pot, said hooked terminals forming spring-catches, substantially as described.
13. A trellis, comprising a body-frame having a hook or clutch at each of its sides, and a brace-frame having a hook or clutch at each of its sides, said brace-frame having a portion of its length above the hooks or clutches twisted together with the body-frame, substantially as set forth.
14. A trellis, comprising a body-frame having a hook or clutch at each of its sides, a brace-frame having a hook or clutch at each of its sides, said brace-frame having a portion 90 of its length above the hooks or clutches twisted together with the body-frame, and a filling secured to the body-frame, said brace-frame extending across the space bounded by the body-frame and connected to said filling, 95 substantially as set forth.

In testimony whereof we have hereunto set our hands this 5th day of June, 1897.
